CAR UNDERFRAME

Filed Aug. 2, 1922

2 Sheets-Sheet 2

This technical drawing illustrates a mechanical assembly, possibly a conveyor system. It features two vertical side panels, each with a hatched pattern. The left panel contains several circular components labeled 19, 20, 22, and 5. The right panel contains components labeled 20, 19, 52, 17, 16, 17, 18, 23, 24, 29, 26, 25, 27, 30, 24, 26, 29, and 28. A horizontal chain or belt is shown at the bottom, supported by a central frame with components labeled 14, 7, 6, 9, 23, 24, 29, 26, 25, 27, 30, 24, 26, 29, and 28. The drawing uses a combination of line art and hatching to define parts and materials.

UNITED STATES PATENT OFFICE.

DONALD S. BARROWS, OF ROCHESTER, NEW YORK, ASSIGNOR, BY MESNE ASSIGNMENTS, TO THE SYMINGTON COMPANY, A CORPORATION OF MARYLAND.

CAR UNDERFRAME.

Application filed August 2, 1922. Serial No. 579,222.

My invention relates to car underframes and, generally stated, involves a metallic built-up structure of uniform strength value adapted to receive the buffing and pulling 5 shocks which exceed the capacity of the draft rigging.

To this end the principal object of my present invention consists in providing a draft arm formed of metal draft plates each adapted to extend upon both sides of the bolster and provided with strengthening means, said strengthening means also extending upon both sides of the bolster and arranged to form a maximum section at the rear thereof and in 10 the plane of the car sill, thereby preventing all tendencies of the frame to tip or rotate in resisting loads under service conditions.

Another object of the invention is to provide a car underframe including metallic 20 draft plates arranged to fit over the bolster and project forwardly and rearwardly thereof, a plurality of reinforcing or stiffening members being connected to the inner and outer faces of said draft plates, some of said 25 stiffening members being arranged to overlie and be connected to the bolster.

A further object of the invention is the provision of a car underframe including in combination draft plates each having a depending portion to which is attached a cheek 30 plate, a tapering portion on each of said draft plates extending rearwardly of the bolster to an advantageous tie point adjacent the center 35 sills, means including a continuous strengthening member arranged throughout the length of the draft plates, and means including gusset plates arranged to unite the lower portions of said draft plates to the bolster.

A still further object of the invention is to 40 provide a car underframe of relatively light weight and maximum uniform strength draft value which can be inexpensively manufactured and easily constructed whereby the load referred to in practice as the eccentric load 45 to which the underframing is subjected, is imparted and brought closer to the center of mass of the underframe, all rotating or tipping tendencies of the frame being as a consequence reduced to a minimum.

50 There are other features of the invention as will be pointed out hereafter in connection with the description of the embodiment of my invention illustrated in the accompanying drawings in which

Figure 1 is a plan view of my improved 55 metallic construction of underframe, an intermediate portion thereof broken away.

Figure 2 is a vertical longitudinal sectional view through the construction shown in 60 Figure 1.

Figure 3 is an enlarged detail horizontal sectional view through the bolster and associated portions of the underframing connected thereto.

Figure 4 is a vertical transverse sectional 65 view on the line 4—4 of Figure 2, viewed in the direction of the arrows.

Figure 5 is a vertical transverse sectional view on the line 5—5 of Figure 2 viewed in the direction of the arrows.

Figure 6 is a vertical transverse sectional 70 view on the line 6—6 of Figure 2, viewed in the direction of the arrows.

In the drawings chosen to illustrate an embodiment of my invention and in which similar reference characters designate corresponding parts in the several views, the car sills or center sills 1 are indicated by the dot and dash lines shown in Figure 2. The center sills may be and are preferably formed of 75 metals such as steel, my improved underframing being associated with and connected thereto in an advantageous manner. The end sill of the car is indicated by the numeral 2 and the striking block by the numeral 3, the latter being 80 provided with face and bottom plates designated by the numeral 4.

My invention may be applied to wooden 85 underframe car sills or to steel center sills, and I do not wish to be understood as limiting my invention in this respect, it being 90 obvious that old and various types of cars can be readily equipped with my improved construction to accommodate draft rigging of a type used under A. R. A. standards and modern service conditions.

While the construction which is the subject of the present invention may be used in connection with any preferred form of draft gear, in the present instance, it is shown as 100 applied to a three-key draft gear of the Farlow type indicated diagrammatically in dot and dash lines in Figure 4.

The draft plates 5—5 which are of a width exceeding the width of the center sills to a 105 considerable extent, are secured to and overlap the inner faces of the sills so that the forward portions of said draft plates extend well

below the sills. Sheet plates 6 are connected by means of rivets 7 to the depending portions of the draft plates, and a plurality of key slots are formed in each cheek plate, said slots being arranged to register with the series of key slots provided in the draft plates, as shown. Each draft plate 5 is recessed or cut away intermediate the ends thereof, said cut away portion forming a bolster receiving opening or recess 8, clearly shown in Figure 2. The upper wall of the opening 8 is preferably adapted to rest upon the top flange of the bolster substantially coincident with the lower face of the center sills.

15 The depending portions of the draft plates are reinforced forwardly of the bolster by a plurality of stiffening members in the form of lower angle bars 9, the vertical flange of the respective bars being connected to the outer faces of the draft plates by means of rivets 10, a relatively large number of the rivets being located near the bolster and other of said rivets serving to connect the cheek plates to the draft plates. The lower flanges of the 20 angles 9 extend outwardly of the draft plates and are connected by a tie member or plate 11 riveted to the lower flanges forwardly of the bolster. A bottom gusset plate 12 is riveted to said tie plate and a portion of the lower 25 flanges of the outer angle members 9, said gusset plate being further connected to the bottom flange of the bolster by means of rivets 13. The stiffening angles 9 extend substantially the length of the draft plates from the 30 front edge of the bolster opening to the forward ends of said draft plates.

Intermediate stiffening members or angle bars are arranged upon the outside of the draft plates and above the angle bars 9, said 35 stiffening angles 14 extending the length of the draft plates forwardly of the bolster and having their horizontal flanges substantially coincident with the lower portion or bottom flange of the center sills. The vertical flanges 40 of the angle members 14 are connected to the draft plates by means of a plurality of longitudinally arranged rivets 15, a greater number of said rivets being provided relatively close to the bolster and other of said rivets 45 serving to connect the cheek plates to the draft plates.

Arranged intermediate the ends of the draft plates and positioned above the stiffening bars 14 are longitudinally disposed 50 stiffening members in the form of angle bars 16 connected to the opposite inner faces of the draft plates by means of relatively closely spaced rivets 17. The vertical flanges of the respective angle bars 16 are adapted to 55 overlie the bolster and project beyond the front and rear edges thereof, the horizontal flanges of said angle bars 16 being connected by means of bolts 18 to the upper flange of the bolster. Each stiffening member 16 is arranged adjacent the bolster recess or opening

in the draft plate and serves to effectively bridge said opening and tie said draft plate to the upper portion of the bolster.

The upper portions of the draft plates are reinforced by an interposed stiffening member 19 preferably of channel shape and arranged to extend throughout the entire length of the draft plates. A plurality of rivets 20 serves to connect the flanges of the channel to the draft plates, filler members 21 being adapted to be inserted so as to accommodate the interposed stiffening member to the spacing between the draft plates and otherwise provide for the utilization of parts of standard measurements, as will be understood.

70 The forward end of the channel 19 is connected to the end sill by means of the angle member 22, as clearly shown in Figures 1 and 4. The forward lower ends of the draft plates are arranged to extend beneath the end sill, as shown.

75 At a point preferably adjacent and slightly in the rear of the bolster the continuous reinforcing or stiffening member 19 is inclined downwardly to conform to the tapering rear end portions 5a of the draft plates. The respective upper and lower edges of the rear end of the draft plates are inclined rearwardly, the lower edge of each of said plates being inclined upwardly and the upper edges of said plates being inclined downwardly, as clearly shown in Figure 2, both of said inclined portions converging to a point back of the bolster and associated framing to provide a maximum cross-sectional area coincident with the plane of the center sills. The 80 tapered rear ends of the draft plates are further reinforced by intermediate stiffening members formed of angle bars 23 having their vertical flanges connected by rivets 24 to the outer faces of the draft plates. The lower edges of the tapered rear ends of the draft plates are reinforced by means of angle members 25 having their vertical flanges connected to the draft plates by a plurality of rivets 26.

85 At the rear ends of said angle members 25 and the continuous channels 19, the connecting rivets are arranged relatively close, as shown, to form a strong connection 90 at this point. The forward portions of the horizontal flanges of the angle bars 25 are 95 transversely connected by means of a bottom tie plate 27, as clearly shown in Figures 2, 3 and 5. A gusset plate 28 unites the rear portion of the draft plates to the bolster, said gusset plate being connected by rivets 29 to the bottom flange of said bolster, and to the bottom tie plate 27 and portions of the horizontal flanges of the angle bars 25 by 100 means of rivets 30, as shown in Figures 2, 3 and 5.

105 An underframe constructed in accordance 110 with my present invention provides a comparatively simple and effective association of 115 continuous and reinforced draft plates hav- 120 125 130

ing their inner ends firmly tied at the rear of the bolster and in a plane relatively close and substantially coincident as far as practical to the plane in which the greatest stress is transmitted to the underframing. It will be apparent that I have provided a strong and relatively light weight underframe for railway cars in which the means reinforcing the draft plates prevents any tendency of the frame to tip, the angular disposition or inclined arrangement of the stiffening members at the rear of the bolster acting, together with the tapered ends of the draft plates, to counteract any tendency of the frame to rotate when subjected to load stresses under service conditions.

While I have illustrated a draft arm in connection with a three-key draft rigging, it will be apparent to those skilled in the art that the device herein illustrated and described may be advantageously utilized in connection with the more modern type of draft rigging shown, for example, in the patent to Symington, No. 1,097,738, dated May 26, 1914.

I have described my invention in detail so that its nature and the manner of using it may be fully understood by those skilled in the art. However, the specific terms herein are used in their descriptive sense rather than in their limiting sense, and the scope of the invention is defined in the claims.

I claim:

1. In a car underframe, the combination with center sills, bolster and end sill, of draft plates having their forward ends extending beneath said end sill and each having a portion fitting over said bolster, means reinforcing said draft plates on each side of said bolster, and angular stiffening members for said draft plates overlying said bolster and reinforcing means.

2. In a car underframe, the combination with center sills, bolster and end sill, of draft plates having their forward ends arranged beneath said end sill and each having a portion fitting over said bolster, means reinforcing said draft plates forwardly and rearwardly of the bolster, stiffening means overlying said reinforcing means and having portions thereof connected to said bolster, and means connecting said reinforcing means to said bolster.

3. In a car underframe, the combination with center sills, bolster and end sill, of draft plates each having a portion fitting over said bolster, means stiffening said draft plates forwardly and rearwardly of said bolster, said rearwardly extending stiffening means terminating in a plane substantially coincident with the lower portion of the center sills, and a continuous reinforcing member overlying said stiffening means and having the rear end thereof terminating at a point substantially coincident with said lower portion of the cen-

ter sills and adjacent the rearwardly extending stiffening means.

4. In a car underframe, the combination with center sills, bolster and end sill, of draft plates each having a portion fitting over said bolster, means reinforcing said draft plates forwardly and rearwardly of the bolster, means connecting said reinforcing means and draft plates to the bolster, and means overlying said reinforcing and connecting means, said last named means being connected to the end sill and having its rear end terminating adjacent said rearwardly extending reinforcing means.

5. In a car underframe, the combination with center sills, bolster and end sill, of draft plates each having a portion fitting over said bolster, means reinforcing said draft plates forwardly and rearwardly of the bolster, stiffening members overlying said bolster and said reinforcing means, said stiffening members being connected to the inner faces of the draft plates and the top flange of the bolster, and a continuous reinforcing member uniting said draft plates above the bolster, said continuous member being rearwardly inclined and connected to said draft plates in a plane passing through the lower portion of the center sills.

6. In a car underframe, the combination with center sills, bolster and end sill, of draft plates each having a portion fitting over said bolster, stiffening members connected to said draft plates and arranged forwardly and rearwardly of the bolster, gusset plates connecting the lower stiffening members to the bottom flange of the bolster, and a channel member connecting said draft plates above the bolster, said channel member being connected at its forward end to the end sill and having its rear portion terminating at a point adjacent the rearwardly extending stiffening members.

7. In a car underframe, the combination with center sills, bolster and end sill, of continuous draft plates each having a portion engaging said bolster, stiffening members connected to said draft plates and arranged forwardly and rearwardly of the bolster, tie plates connecting said draft plates and stiffening members upon each side of the bolster, gusset plates connecting the tie plates and some of said stiffening members to the bolster, and a continuous member connecting said draft plates above the bolster, said continuous member being connected at its forward end to the end sill and having its other end terminating at the rear of the bolster.

8. In a car underframe, the combination with center sills, bolster and end sill, of continuous draft plates bridging the bolster, stiffening members connected to said draft plates upon both sides of said bolster, and a continuous member connecting said draft

- plates and overlying said stiffening members, said continuous member being connected at its forward end to the end sill and terminating at a point in the rear of the bolster.
5. 9. In a car underframe, the combination with center sills, bolster and end sill, of draft plates each provided with a bolster receiving opening, means reinforcing said draft plates adjacent said opening forwardly and rearwardly of the bolster, means connecting said draft plates to the bolster adjacent said opening, and a continuous member connecting said draft plates and spaced from said bolster receiving opening, said continuous 10 member having its forward end connected to the end sill and its opposite end terminating at a point in the rear of said bolster.
10. In a car underframe, the combination with center sills and bolster, of draft plates 20 each provided with a bolster receiving opening, means reinforcing said draft plates adjacent said opening forwardly and rearwardly of the bolster, means reinforcing and connecting said draft plates to the upper portion of said bolster adjacent said opening, and means connecting said draft plates to the lower portion of said bolster adjacent said opening.
11. In a car underframe, the combination 30 with center sills and bolster, of draft plates connected to said center sills and each provided with a bolster receiving opening, means reinforcing said draft plates adjacent said opening and overlying said bolster, means 35 including a gusset plate connecting the draft plates to said bolster, and a continuous member spaced from said opening and overlying the bolster, said continuous member connecting said draft plates and having portions 40 terminating forwardly and rearwardly of said bolster.
12. In a car underframe, the combination with center sills and bolster, of draft plates each having a portion fitting said bolster, 45 depending portions provided on said draft plates forwardly of the bolster, cheek plates connected to said depending portions, reinforcing means for said draft plates, rivet means connecting said draft plates, reinforcing means and cheek plates, and a stiffening member extending substantially throughout the length of said draft plates and having its rear end terminating in the rear of the bolster in a plane passing through the center 55 sills.
13. In a car underframe, the combination with a bolster, of car sills, draft plates extending along said sills and each formed with an opening adapted to receive said 60 bolster, and means connecting the upper and lower portions of said draft plates to the respective upper and lower portions of said bolster adjacent said opening.
14. In a car underframe, the combination with center sills, end sill and bolster, of a pair 65 of draft plates connected to the center sills upon both sides of the bolster and extending under the end sill, a depending portion provided on each of said draft plates, cheek plates connected to said depending portions, 70 means including angle members connected to said cheek plates and draft plates and arranged upon the outer faces of the latter, and a reinforcing member connecting the upper portions of said draft plates, said reinforcing member being arranged to overlie the bolster and having its opposite ends terminating in a plane passing through the center sills.
15. In a car underframe, the combination 75 with car sills, end sill and bolster, of draft plates connected to the center sills and extending under the end sill, and reinforcing means arranged above and below said bolster and extending rearwardly thereof, said reinforcing means converging to a point in the rear of the bolster adjacent the car sills.
16. In a car underframe, the combination 80 with car sills, end sill and bolster, of draft plates connected to the car sills having portions extending under said end sill, and continuous reinforcing means arranged above said bolster, said reinforcing means having its forward end connected to the end sill and its rear portion inclined downwardly to a 85 plane passing through the lower portion of the car sills.
17. In a car underframe, the combination 90 with a bolster, of center sills, draft plates having openings adapted to receive the bolster, depending portions provided on said draft plates at their forward ends, tapered portions formed on the rear ends of said draft plates, a plurality of stiffening members for said depending and tapered portions, 95 and a reinforcing member connecting the draft plates above said stiffening members substantially throughout the length of said draft plates.
18. In a car underframe, the combination 100 with center sills and bolster, of continuous draft plates connected to said center sills and to each other along substantially the full length thereof, each of said draft plates being provided with a recess adapted to receive the bolster, and means connecting portions of said draft plates to the bolster.
- In testimony whereof I affix my signature.

DONALD S. BARROWS.
